TURRET GUN GAS EJECTION SYSTEM

Frank Warlick, Washington, D. C.

Application September 20, 1950, Serial No. 185,899

1 Claim. (Cl. 89—1)

(Granted under Title 35, U. S. Code (1952), sec. 266)

This invention pertains to a rapid fire turret gun assembly and more specifically to the new and novel system and arrangement of parts of the gas ejection system for the gun slide assembly thereof whereby the ejection of spent powder gases is accomplished automatically and is correlated with the mechanical actions of the gun slide system in firing and in case ejection action.

This invention is particularly adapted for use with major caliber guns of a type adapted for usage of pre-packed cased semi-fixed ammunition of large bore, as for example, 8 inches. The prior art naval turrets mounting large bore guns have heretofore incorporated in their apparatus and method of operation, the usage of projectile propellant powder charges packaged in cloth bags which are manually handled and loaded by attendants at the gun loading station. In the operation of a gun of this type the gun breech is swabbed after firing of each round to expel spent particles of powder and burned portions remaining after the firing of the powder charge contained by the bag. It is desirable to have these gases expelled through the gun muzzle in order that the fumes may not remain and contaminate the interior of the turret house where the gun crews are working. While inside of the turret house may be maintained at a slight positive pressure over the atmospheric pressure outside of the gun house to provide draft for removal of spent powder fumes and gases, such a system does not provide sufficient and rapid ejection of these undesirable gases. Moreover the manual swabbing of the gun breech along with positive gun house pressure as a means of exhausting these gases and spent powder particles is relatively slow and is not well adapted for use with rapid fire gun assemblies.

The gas ejection incorporated in the gun slide assembly of the gun with which the present invention is intended to be used are well adapted for use with semi-fixed cased ammunition rather than the powder bag type of ammunition previously used in guns of similar large bore. The incorporation of semi-fixed case ammunition therein as handled by the novel structural embodiment of the turrets is set forth and described in greater detail in the copending application of Philias H. Girouard et al., Serial No. 153,262, filed March 31, 1950. The arrangement of the control device of the instant invention which is associated with the mechanical elements of the gun case ejection system is adapted to be coupled to the upper end of the extractor spade wherein, after hydraulic action by the extractor operating cylinder a valve is opened in the gas ejection system to exhaust spent gases as the empty case is removed from the breech. The present system of gas ejection is well adapted for operation with a high speed gun handling system and operates automatically at a predetermined time in the cycle of gun operation.

The instrumentalities effecting automatic gas ejection after firing are mechanically controlled by action of the extractor spades and are additionally automatic in the pressure control arrangement. This is accomplished by

2

a suitably provided pilot valve on a second one of the valves of the instant system.

The instrumentalities effecting automatic gas ejection after gun firing are mechanically associated with the blow valve of this system, and being connected to the extractor operating mechanism are positively associated therewith so that gas ejection takes place immediately after the empty case leaves the gun breech. Each such system is also provided with an additional jet element which functions to maintain the breech bolt operating assembly in a clean and working condition at all times. This insures that the breech actuating elements are always in an operative condition and that improper operation of the breech mechanism and malfunction of the gun system is greatly reduced or completely eliminated.

The structure and positional arrangement of the elements of the gas ejection system for use with a gun slide assembly are such as to permit the mounting of all elements on the gun slide and slide housing. A suitable sliding joint is provided between the housing and slide to permit pneumatic communication between the slide and moving assemblies of the housing to effect gas ejection at the gun breech. A suitable swing joint assembly is shown and described with relationship to this system and provides a means for the passage of air under pressure from a suitable air source such as the ship's compressor supply to the assemblies mounted on the gun slide.

A gas ejection system is thus provided wherein the gun and slide assembly and the movable housing thereof may be loaded and fired automatically in any position of gun elevation and whereby gas ejection after firing will take place irrespective of the position of the gun. The instant invention eliminates the necessity for cumbersome and manually handled swabs for powder bag fragment ejection, spent gas exhaust and unburned powder disposal and in addition effectively eliminates the contamination of the air supply in the gun turret house.

One object of the present invention is the provision of a fully automatic gun loading and firing system in which many of the foregoing disadvantages are obviated and which is adapted to perform satisfactorily all the essential functions of the systems heretofore devised or now in general use and in which the possibility of contamination of the air supply in the gun house is greatly reduced and wherein apparatus malfunction or failure due to the effects of burned powder getting into working parts thereof is reduced to a minimum.

An additional object of this invention lies in the provision of a gas ejection system adapted for use with rapid fire rate gun mechanism of a major caliber turret assembly.

Another object of this invention lies in the provision of a gas ejection system which is adapted for use with semi-fixed cased ammunition.

An additional object of the invention is the attainment of new and improved gas ejection after gun firing which is positively mechanically coupled with the action of case extraction.

Another object of the invention lies in the accomplishments by improved means of ejection of powder gases by the provision of air passages at a plurality of points within the gun breech proper.

Additionally, it is an object of this invention to provide a gas ejection system capable of ejecting spent gases at any angle of gun elevation.

It is also an object of this invention to provide automatic gas ejection in synchronized time relationship with the powder case extracting action whereby spent powder gases are prevented from entering the gun house chamber after the empty cartridge case is extracted from the gun breech.

A further object resides in the provision of a gas ejection system in which the elements thereof are adapted for mounting on the gun slide and housing assembly adjacent the gun trunnions for movement with the gun in all positions of the gun in elevation.

Additional objects and advantages of this invention will be apparent from the following description of a preferred embodiment of the invention and the accompanying drawings wherein:

Fig. 1 is a generally schematic view of the gas ejector system showing its general arrangement with respect to a suitable gun slide and gun housing assembly;

Fig. 2 illustrates the gas ejector pilot and flow control valve in vertical section;

Fig. 3 is a view in elevation of the gas ejector blow valve and illustrates its relationship with the tripping mechanism;

Fig. 4 is a view showing the air passages in the gun housing and gun breech assembly and;

Fig. 5 is a sectional view of the gas ejector blow valve.

Referring now to Fig. 1 of the drawings, the showing is that of the arrangement of an assembled air line system 1 having valves and lead connections therefrom to connect with an air supply source 2 such, for example, as from the ship's supply. The gas ejector system receives air from the source and directs a plurality of jets of compressed air to the powder chamber and gun bore at 3 to expel gases from the muzzle of the gun after firing. Control of the gas ejection is by means of a valve 4 which is arranged to be actuated by movement of one of the extractor spades shown, for example, at 5.

The principal components of the gas ejecting system as shown in Fig. 1 are a manifold and pipe system 6 on the slide and gun housing and the swing joints 7 connecting the supply line 8 associated therewith, with a pipe line 9 of the sliding expansion joint 10. A pilot valve 11 and flow control valve 12 of Fig. 2 are associated with a blow valve 13 of Figs. 1, 3 and 5. A tripping mechanism 14 is associated with the herein above described blow valve 13 and is coupled with a spade member at 5 of the extractor. The system also includes an air strainer 15, a manual gate valve 17 for the purpose of shutting off ship's air supply, and the pipe line 18 which is connected to the system at the cutoff gate valve 17. The shut-off valve is preferably located in the gun pocket below the slide trunnion 16. The air strainer 15 is of conventional design and permits flow upwardly thru a lower manifold unit 19 and therefrom thru the swing joint 7 to an upper manifold 20 on the gun slide. The upper manifold is preferably located adjacent the gun turret trunnion. Air flows upwardly to the flow control valve 12 thru the expansion joint stuffing box 21 to the slide housing assembly 22. Two air lines 23 and 24 extend from the upper manifold as shown in Fig. 1. One line carries air supply to the blow valve 13 located on the slide at the gun breech, and extends from the blow valve to pilot valve 11 on the slide. The second of these lines carries air supply from the upper manifold directly to the flow control valve 12, and extends rearwardly thru expansion joint 10 in the slide to the manifold 25 on the gun housing. From this manifold the system distributes air to two nozzles in the breech block guide at 26 and 27 and to jet 28 in the breechway. The arrangement of these jets in the breech block is as shown in Fig. 4. The air delivery from the manifold to the gun breech is by pipelines 29 and 30 and air passages 31 and 32 to the gun housing as shown in Figs. 1 and 4. Delivery to the jet 28 is by suitable tubing 33 and passage 34. The jet 28 is an accessory outlet of the system and functions to blow off any particles of foreign matter that lodge on the top surfaces of the bolt cam.

The swing joints of the gas ejector system are conventional high pressure flexible pipe connections of goose-neck type and are arranged to provide positive air seal thruout their bending movement by means of an assembly including a male and female elbow. These elbows are

arranged with double row ball bearings therein, but not shown, and suitable neoprene sealing rings, also not shown. The sealing rings function to prevent leakage of air under pressure from the joints of the system.

5 The sliding expansion joint is a telescoping pipe connection which carries compressed air from the fixed pipe installation of the slide to the movable gun housing. The main part of the joint comprises a stuffing box 21 and an outer sleeve member 35 arranged in a telescopic arrangement with an inner pipe 36. The mounting of the expansion joint in the illustrated embodiment, is in a bore of the slide recoil brake assembly. It is a conventional pipe stuffing box through which moving elements move when the gun recoils and counter-recoils. A pilot valve 10 of the system as shown in Fig. 2 is a conventional valve device which functions to automatically control the period of air flow in the pipe system through the flow control pipe 12 by acting as a means of actuation for the flow control valve. This pilot valve is connected to receive air 15 under pressure from the blow valve to provide opening action for the flow control valve. Construction of this assembly is such as to include a poppet-type air valve member 37 having a plunger unit 38 thereof mounted so as to be on a common support with respect to the pilot valve. The construction and functional arrangement of 20 the pilot valve-flow control-valve-assembly includes a poppet-type air valve member 39 of the flow control part of this assembly. It is spring loaded at 40 and arranged to seat at 41. The plunger unit shaft 42 is integral with the 25 valve member 39, is on a common axis and adapted to be engaged by a shaft 43 of the piston 49 of the pilot valve. The flow control valve is adjustable and is caused to open by action of the pilot valve and is returned to seated position by the action of the spring 40 which is located under the valve closing member 39, and by air pressure applied thereto.

30 The functioning of this system is such that when air is admitted to the upper chamber of the pilot 11 with the air cutoff, at 41 in the flow control valve 12 the plunger 43 is depressed to open the poppet 39. The air in the upper chamber is allowed to escape to a seepage hole 45 of an air control screw 46. The poppet valve stem 42 and the plunger 43 move upwardly under spring action to close the poppet valve 39 as air in the upper chamber escapes through the orifice 47 and through the seepage hole 45.

35 The initial movement of the poppet plunger occurs when air is ported through the upper chamber by opening the blow valve. The blow valve and its tripping device 48 are mounted on the rear of the recoil brake assembly as shown at 13 in Fig. 1. The valve as shown in detail in Fig. 5 is a small poppet type and is adapted to be opened by the valve operating lever 48 which is pivoted on its mounting frame bracket at 54. This mounting lever is 40 tripped by the stroking movement of one of the extractor spade cylinders. It is this tripping arrangement which holds the valve open only during the brief period of extractor spade movement. The pilot valve 11 is connected with the blow valve by the connection 23 which runs from the outlet of the blow valve to the inlet of the pilot valve cylinder. The inlet of the blow valve is connected by 45 means of line 8 with the air source 2. Adjustment is provided at 50 on the valve operating lever arm to provide a means of regulating the spade position at which the blow valve will open.

50 The gate type cutoff valve 17 and the air strainer associated therewith are of conventional design as is the blow valve 4; the details thereof being shown in Fig. 5 of the drawing. The details of the gate valve 17 which is of a globe type, are not shown. This valve enables 55 positive cutoff of the ship's air supply. The strainer unit is a straining device which has therein, a removable element of conventional design which may be cleaned or replaced as desired.

55 The mounting of the gas ejector blow-off valve is as shown in Fig. 3 and comprises a valve bracket 51 supporting

the blow valve 4. A pin member 52 is arranged to actuate the arm assembly 53 which is mounted for pivotal movement on pin 54 and which is adjustable at 50 by means of a screw and locknut assembly 55 to control the degree of actuation of the valve by arm movement. It is this screw which actuates the plunger of the valve. The operating lever is arranged to connect with the pin roller shaft of the extractor cylinder assembly. The gas ejection system of the invention may be adapted for either right or left handed gun use. The elements thereof are generally similar but of opposite hand, as the case may be. The elements affected by such a design variation are the valve tripping mechanism 48, the sliding expansion joint 10, the manifolds 6 and 19 and the piping associated therewith.

The operation of the gas ejection system is such that air is permitted to flow from the ship's source thru the globe gate valve block and thence through line 18 to the air strainer where foreign particles suspended in the air are removed. After passage thru the air filter the air is conducted by pipe 8 through the swing joints 7 at the lower manifold to the upper manifold and thence to the flow control valve 12. The poppet 39 of this valve is opened to permit air flow in the direction shown in Fig. 2 upon actuation by pressure applied to the upper surface of the piston 49 of the floating piston type control unit 11. Flow from the poppet valve is carried to a manifold on the housing by means of the sliding valve joint which provides a coupling arrangement between the gun slide and the slide housing at any position of the breech in recoil and counterrecoil. The pressure flow from the manifold on the housing is thru the lines 29, 30 and 33. Passages 31 and 32 are connected to introduce air into the interior of the gun breech while passage 28 is for the purpose of directing an air jet against the elements of the breech bolt cam actuating assembly.

The operation of the elements of the system which permit and control the period and sequence of gas ejection is accomplished by the flow of air thru the blow valve upon actuation by the arm thereof and the elements associated with the extractor spade roller. Upon opening to permit flow thru the valve 4 from line 24 to line 23 air pressure is introduced thru the inlet at the top of the floating piston chamber associated with the poppet valve. This pressure forces the piston down to open the poppet valve. The arrangement additionally includes an exhaust orifice from the upper chamber of the floating piston to provide slow leak off of pressure after closing of the valve 13 upon additional movement of the extractor spade. As the pressure is permitted to leak off at this orifice, which is adjusted by means of the screw adjustment on the top of the piston cylinder head, the spring beneath the poppet valve acts to close this valve. Pres-

sure is reintroduced above the floating valve on the next cycle of ejection operation.

Obviously, many modifications and variations of the present invention are possible in the light of the above teaching. It is therefore to be understood that within the scope of the appended claim the invention may be practiced otherwise than specifically described.

The invention described herein may be manufactured and used by or for the Government of the United States of America for governmental purposes without the payment of any royalties thereon or therefor.

What is claimed as new and desired to be secured by Letters Patent of the United States is:

In combination in a gas ejection system for a major caliber gun comprising a source of air under pressure and including a pipe line circuit system connected thereto and having a plurality of exhaust elements associated therewith, a control initiating means operatively associated with the gun assemblies and adapted for actuation at empty case ejection, manifolding means adapted to receive the air under pressure and disburse it through the plurality of outlets, a sliding joint element arranged to permit flow from the gun slide to a gun housing of the gun system in any position of the housing in recoil or counterrecoil, a valve type operation initiating means adapted for coupled arrangement with the extractor mechanism of the gun system, a flow control means in said piping system to control flow from said source to said manifold, said last named means being pneumatically coupled to the means responsive to case ejection to control the action of the said air flow control means wherein said air flow control means comprises a poppet type valve assembly having a floating piston and piston rod mounted thereon, a cylinder for reception of said piston, an inlet port therein in communication with the valve of said operation initiating means, and vent means in said floating cylinder assembly for controlling the period of air discharge after the cessation of actuation of the said first named means.
